UNITED STATES PATENT OFFICE.

FRANK SCHILLING, OF MUNCIE, INDIANA, ASSIGNOR TO THE MUNCIE
GLASS COMPANY, OF SAME PLACE.

DESIGN FOR A BOTTLE.

SPECIFICATION forming part of Design No. 31,500, dated September 12, 1899.

Application filed August 16, 1899. Serial No. 727,450. Term of patent 7 years.

To all whom it may concern:

Be it known that I, FRANK SCHILLING, a citizen of the United States, residing at Muncie, in the county of Delaware and State of Indiana, have invented and produced a new and useful Design for Bottles, of which the following is a specification, reference being had to the accompanying drawings, forming part thereof, and in which similar letters of reference indicate corresponding parts in both views.

Figure 1 is a perspective view of a bottle, showing my design. Fig. 2 is a perspective view showing the other side thereof.

As shown in the drawings, the leading or material feature of my design consists of the

representation of leaves A and blossom B, arranged around the shoulder of the bottle, and the representation of a cabin C, tree D, and kettle E, hanging from the crane F, arranged around the lower portion of the bottle. 20

Having thus described my invention, what I claim as new, and desire to secure by Letters Patent, is—

The design for a bottle, substantially as shown and described. 25

In testimony whereof I have signed my name in the presence of two witnesses.

FRANK SCHILLING.

Witnesses:

E. O. WARD,
CHARLES WOLF.
